(57) **CLAIM**

The ornamental design for a key ring holder with multipurpose tools, as shown and described.

DESCRIPTION

FIG. 1 is a perspective view of a key ring holder with multipurpose tools, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a referential operational front elevation view thereof when the multipurpose tools are separated outside, wherein the broken lines are shown for illustrative purposes only and form no part of the claimed design.
